UNITED STATES PATENT OFFICE.

ALFREDO MUSSO, OF NEW YORK, N. Y., ASSIGNOR OF THREE-FIFTHS TO
ANTHONY MASINO AND LAWRENCE J. BARRETT, OF PORT READING,
NEW JERSEY.

ELECTRIC SHOVEL.

SPECIFICATION forming part of Letters Patent No. 740,165, dated September 29, 1903.
Application filed May 27, 1903. Serial No. 158,974. (No model.)

To all whom it may concern:

Be it known that I, ALFREDO MUSSO, residing at New York, in the county of New York and State of New York, have invented certain new and useful Improvements in Electric Shovels, of which the following is a full, clear, and exact description, such as will enable others skilled in the art to which it appertains to make and use the same.

10 The invention relates to excavators, and more particularly has reference to a system and apparatus for progressively excavating earth or soil, together with provisions for automatically advancing the apparatus and transferring and loading the dirt into cars in a most rapid and effective manner. Heretofore in such apparatus the work has been laboriously carried on with large gangs of workmen and cumbersome machinery, and it has 15 generally been necessary to lay improvised tracks on uneven ground by which the dirt-cars could be conducted to one side of the shovel, where they were loaded either entirely or partially by hand.

20 The object of my present invention is to provide an apparatus of increased efficiency designed to overcome these and other disadvantages of previous systems, whereby the work of cutting, tunneling, or otherwise excavating into the earth may be progressively carried on and completed with a minimum 25 number of workmen and the greatest saving of time and expense. The means whereby these desirable results are secured is fully described in the accompanying specification and drawings and is more particularly pointed out in the appended claims.

Referring to the drawings, Figure 1 is a general side elevation view, and Fig. 2 is a plan view, of my improved apparatus. Fig. 3 is a transverse sectional view of the shovel operating and forwarding mechanism, taken in a plane just above the truck-wheels and showing some parts in plan. Fig. 4 is a detail of the shovel proper. Fig. 5 is a vertical sectional view of the magazine and means for storing the flexible track. Fig. 6 is a transverse section of a part of Fig. 5. Figs. 7 and 8 illustrate the track with a switch applied to it. Fig. 9 is a sectional detail of the shovel-operating mechanism. Figs. 10 to 13 are dia-

grammatic representations of the car-interchanging devices.

The apparatus is entirely self-contained and, considered functionally, comprises three parts which mutually coöperate to accomplish the useful result above referred to. These parts are the digging or shovel mechanism, the means for intermittently advancing it toward the work, and the transporting and loading apparatus, and a full description of each follows below.

The body of the apparatus comprises an oblong car or box A, suitably mounted on trucks by which it may be advanced along the tracks 55 B while the apparatus is in operation or moved over ordinary railroad-tracks for transportation. On the forward end of the car-body is rigidly mounted a projecting bracket, and to this bracket a journal-support D, having an inclined arm D', is pivoted to swing laterally. The arm D' is slotted at its upper end to receive a cross-head E, adapted for reciprocating movement therein, and is also provided with oppositely - extending fixed lugs D², 75 slightly offset from the slot in the arm D'.

The shovel F is composed of box-like compartments having plowshares or scoops at their edges, as shown in Fig. 4, and is carried by two side arms F', pivoted at their other ends to the cross-head E and slotted, as indicated, to straddle the fixed offset lugs D², where by the reciprocation of the cross-head in the slotted arm D' causes the shovel to swing forward with a scooping action to the 80 position shown in dotted lines in Fig. 1 and deposit the dirt gathered by it into the hopper G, from whence the dirt is carried to the dirt-cars upon a suitable conveyer, as will be 85 presently described.

The cross-head E may be reciprocated in any convenient manner, and in the accompanying drawings I have shown a simple form of gearing, in which two pitmen E' are connected, respectively, to the cross-head E on 90 the opposite sides of the arm D' and to wrist-pins E² on the crank-wheels H, which latter are mounted on the ends of a transverse shaft journaled in the arm-base D and driven by 95 means of chains and sprockets from the miter-gears H'. The gears H' are in turn driven by 100 a vertical shaft passing through the pivot of

the journal-support and receiving power through universal shafting I' and other suitable gearing from the electric motor I , mounted beneath the car-body, as shown in Figs. 1 and 3.

The laterally-pivoted shovel mechanism above described is caused to swing slowly from side to side, so as to dig in all directions in front of the car, by means of a segmental gear J , rigidly connected to the pivot of the swinging journal-support D . The gear J is engaged by a rack J' , secured to the nut J^2 , Fig. 9, mounted on the double-pitched screw-shaft J^3 . As the shaft J^3 is rotated by its sprocket-chain connection with the armature-shaft of motor I the nut and rack are caused to travel slowly back and forth and move the shovel mechanism from side to side.

The hopper G is semicircular in form and disposed above the shovel mechanism so as to conduct the excavated dirt therefrom to an endless conveyer K , by which it is carried to a chute or distributor L in the rear of the apparatus and uniformly loaded into the cars M , as will be presently described.

The endless conveyer K is of any suitable construction and travels on the tracks K' on the top of the car-body. It is driven from the motor I by ordinary gearing, which it is unnecessary here to describe, or it may be driven by means of a separate motor carried for that purpose within the car, and it may also be provided with stationary side walls K^2 for preventing the excavations from falling off.

When power is applied to the parts above described, it will be obvious that the shovel will rapidly scoop up dirt in front of the apparatus as it slowly swings from side to side and deposit it in the hopper and that the dirt will be immediately carried by the endless conveyer and dumped into the cars M . As soon as the apparatus has removed the dirt immediately in front of it it is necessary that it be advanced to act upon a fresh portion, and to this end I have provided a gearing connection (shown in simple form in Figs. 1 and 3) which is adapted to connect the wheel-axle of the truck with the motor at the end of each lateral movement of the shovel mechanism. The connection referred to comprises a pair of idler-gears slidably mounted in brackets on the car-body and adapted to be moved into engagement with gears 2 and 3 by means of the two connected levers 4, 4, moved by the connecting-rods 4^a 4^a, pivotally connected to the segmental gear J and held as said gear rocks momentarily in the position shown in Fig. 3. As they recede from their extreme position the connected gears slide out of engagement and the driving connection is discontinued, but the momentary connection has sufficed to move the apparatus a step forward in the direction of the work. At the end of each lateral movement of the shovel the same operation is repeated, as will be obvious from a consideration of Fig. 3.

As the apparatus advances toward the work it lays its own track B , which is of the flexible jointed variety, and the greater part of the car-body is occupied as a magazine for storing the track or so much of it as is not in use, from whence it may be automatically drawn as required by the advancing movement of the apparatus. For this purpose a number of rollers 5, Figs. 5 and 6, are journaled horizontally in the car-body, at the approximate ends thereof, and are provided with worm-gears 6, uniformly driven by means of the upright worm-shafts 7, which are geared together by sprocket-chains 8 and connected with the motor I by means of sprocket-chains 9 and 10, vertical shaft 11 and bevel-gear 12 meshing with gear 13 on the armature-shaft. The latter gear is adapted to be clutched to 85 rotar with the motor armature-shaft by means of a suitable clutch 14 and lever, but may also be connected with a reversing mechanism, (not shown,) if desired.

The flexible track is disposed alternately over the rollers 5 at opposite ends of the magazine and from thence passes down through an aperture in the floor to the ground in front of the forward truck-wheels, as shown in Fig. 1. The cables or flexible part B' , to which the sections B^2 are secured, are extended beyond the magazine end of the track proper and wound over a drum or roller 5', geared to the top roller 5, so that after the whole of the track proper has been drawn out—say until the last section B^2 is in front of the trucks—it may be properly guided back over the rollers when the latter are rotated by the worm-shafts 7.

During the winding up of the track it is obvious that provision must be made for temporarily holding and removing the apparatus from it, and the lifting-jacks 16, adjacent each truck, are intended to serve this purpose. They may be of any ordinary construction adapted to lift the trucks bodily from the track and are driven by suitable electric motors inclosed in casings 17, which also being of ordinary construction and well understood do not require detailed illustration or description.

While the apparatus is temporarily elevated off the track the winding-rollers are set in motion by slipping the clutch and the track is drawn up from the rear and stored in the magazine. The car-body is then lowered onto the tail end of the track and is ready to be farther advanced in the automatic manner above described.

Fig. 7 illustrates in detail a plan view of the track, showing it to be provided with cross-ties and flexible cables or stringers. The track is also adapted to form a roadway for the dirt-cars M , Fig. 1, which run under the chute L and when loaded thereby are moved back over the flexible track and onto other ordinary tracks, if desired, to their destinations.

As the machine is adapted for practically continuous action, and as the excavated dirt

is in consequence continually delivered to the chute L, it is desirable to substitute empty cars for loaded ones with the greatest rapidity, and for this purpose I provide a switch O, which may be laid upon and over the track B at any point thereon, but preferably immediately behind the chute L. The crossing rail of the switch is notched at O', as shown in Fig. 8, for the passage of the flanges of wheels on track B. The empty cars may be kept in readiness either on the main track or the switch, and as one becomes filled it may be moved out of the way on one track and an empty car put in its place beneath the chute from the other.

A further refinement of my invention provides means whereby the interchange of cars above referred to may be automatically effected and whereby the car may be gradually advanced while beneath the chute so that it will be uniformly loaded. In the embodiment of this means each car has a driving-motor and is provided or connected with a source of power which is controlled by means of a slide-controller P, Figs. 10 to 13, operated by a buffer plate, with a side arm P' extending laterally therefrom.

As a loaded car passes down one track it trips the lever Q, which is pivoted to a fixed point, and operates the extended arm P' and controller P of the next empty car which is waiting to be filled at the point shown in Figs. 10 and 11. The effect of this operation on the empty car is to shift the movable contacts R into engagement with the fixed contacts R', so as to connect its motor into the circuit of the source of current X and start the car forward beneath the chute L, whereupon it is uniformly filled with dirt until the buffer plate strikes the fixed stop S and shifts the controller to its other extreme position, whereby current is immediately supplied to the car-motor in a reverse direction, and the car backs quickly out from under the chute and over the switch-track O, operating the trip-lever 2 for the next empty car, and so on with each succeeding car.

A cabin or pilot-house is provided on the top of the car, in which an operator may control such circuits and levers as are necessary to be manually controlled in the operation of the apparatus.

It will be observed that improved means may be provided whereby the transmission of power from the motors to the several moving parts may be materially simplified and made more closely to conform with the requirements of the apparatus without departing from the spirit and scope of my invention. The shovel mechanism may also be supplanted by other forms capable of depositing the dirt in a conveyer and the apparatus may be generally improved in details, all of which improvements are intended to be included and covered by the annexed claims.

I claim—

1. An excavating apparatus comprising a car-body and a shovel mechanism mounted on the forward part thereof, in combination with an automatic mechanism for advancing the apparatus toward the work. 70

2. An excavating apparatus comprising a car-body and wheels upon which the said body is movable, a shovel mechanism mounted on said body and means for actuating the same, 75 in combination with means controlled by said shovel mechanism for driving said wheels, whereby the apparatus may be automatically advanced toward the work.

3. An excavating apparatus comprising a car-body and wheels upon which the said body is movable, a shovel mechanism mounted on said body and means for imparting lateral movement to the same, in combination with a motor and means controlled by said shovel 85 mechanism for connecting said motor to rotate the wheels at the end of the lateral movement of said shovel mechanism.

4. An excavating apparatus comprising a movable car-body and shovel mechanism 90 mounted on the fore part thereof and a conveyer extending from the shovel mechanism to the rear of the apparatus, in combination with means for advancing the apparatus in the line of its work. 95

5. An excavating apparatus comprising a shovel mechanism mounted on the fore part thereof and a conveyer extending from the shovel mechanism to the rear of the apparatus, in combination with a hopper above said 100 mechanism adapted to receive excavated dirt from said shovel and conduct it to said conveyer.

6. An excavating apparatus comprising an endless conveyer and a hopper for conducting 105 the dirt thereto, a shovel mechanism located below said hopper and provided with means for depositing the dirt upon said hopper.

7. In excavating apparatus, a shovel mechanism comprising a support and a reciprocating cross-head mounted thereon, a lug on said support offset from the line of travel of said cross-head, an arm pivoted to said cross-head and engaging said lug, and a shovel mounted on said arm. 110

8. In excavating apparatus, a shovel mechanism comprising a support and a vertically swinging shovel mounted thereon, a reciprocating cross-head for swinging said shovel and a crank-wheel for actuating said cross-head. 120

9. An excavating apparatus comprising a support and a shovel mechanism pivoted for lateral movement thereon, means for causing such movement, comprising a rack and segmental gear, a nut secured to said rack and a double-pitched screw-shaft for reciprocating said nut. 125

10. An excavating apparatus comprising a car-body and wheels upon which the said body is 130

movable, a shovel mechanism mounted on said body and means controlled by the shovel mechanism for advancing it toward the work, in combination with a flexible track stored in said body and adapted to be automatically laid in front of said wheels as the apparatus advances.

11. An excavating apparatus comprising a movable car-body and shovel mechanism carried thereby, a flexible track upon which the car-body is adapted to move and a removable switch placed on said track behind the car-body.

12. In a progressive excavating apparatus, the combination with a flexible track carried thereby and supplied thereto as the apparatus advances, of a dirt - car provided with a motor and adapted to receive the excavated dirt from said apparatus.

13. The combination with an excavating apparatus and a flexible track carried thereby upon which said apparatus moves, of a motor-driven dirt-cart provided with a con-

troller, and adapted to move on said flexible track, and a stop on said excavating apparatus operating said controller.

14. In excavating apparatus a dirt-car provided with a driving-motor and a controller for reversing the direction of movement thereof, and a buffer - plate on the car connected with said controller.

15. In excavating apparatus, the combination with a dirt-car provided with a driving-motor and a controller for reversing the direction of movement thereof, of a lateral extension connected with said controller, a tripping-lever secured to a fixed point and adapted to engage said extension, whereby the passage of a car on an adjacent track will operate the said controller.

In testimony whereof I affix my signature in the presence of two witnesses.

ALFREDO MUSSO.
